TREATMENT OF HYDROCARBON OILS

Jacque C. Morrell, Chicago, Ill., assignor to Universal Oil Products Company, Chicago, Ill., a corporation of Delaware

Application August 10, 1936, Serial No. 95,166

4 Claims. (Cl. 196—48)

This is a continuation-in-part of my co-pending application Serial #524,430, filed March 23, 1931.

5 The invention relates to an improved process for the cracking of hydrocarbon oils of relatively high-boiling characteristics to produce substantial yields of gasoline and a coke-like residue and the simultaneous cracking of lower boiling oils, such as gasoline of inferior antiknock value 10 or distillate containing the same, for the purpose of improving the antiknock value of the motor fuel, accompanied by further conversion of the insufficiently cracked intermediate products of 15 the process.

15 The process employs two charging stocks, one of which comprises hydrocarbon oil of high-boiling characteristics or of relatively wide boiling range such as crude petroleum, topped crude, gas oil, or the like, and which is preferably a 20 virgin oil containing no substantial quantity of materials of poor antiknock value boiling within the range of gasoline. The other charging stock preferably is also a virgin oil which may comprise either gasoline or gasoline fractions of inferior 25 antiknock value or distillate containing the same and which is preferably of lower boiling characteristics than the first mentioned charging stock. The first and second mentioned charging stocks will, for the sake of convenience, be referred to, respectively, as primary charging stock 30 and secondary charging stock, although this terminology is not to be construed as designating the relative quantities of the two.

The process is preferably conducted in a 35 cracking system of the type employing a vertically disposed reaction chamber operated at substantial superatmospheric pressure followed by a vaporizing and separating chamber preferably operated at substantially reduced pressure relative to that employed in the reaction chamber and which, in the present process, is preferably operated as a coking zone, both vaporous and liquid conversion products being discharged from 40 the lower portion of the reaction chamber into 45 the coking chamber. Separate heating coils are employed for independently heating the primary and secondary charging stocks each to the desired temperature, preferably at a substantial superatmospheric pressure, the heated products 50 from the primary charging stock heating coil being introduced into the reaction chamber, and preferably into the upper portion thereof, wherein both their vaporous and liquid components pass downwardly through this zone and are subjected to appreciable continued cracking therein,

prior to their discharge from the lower portion thereof. The secondary charging stock is heated to a substantially higher cracking temperature than the primary charging stock and highly heated products from the secondary charging 5 stock heating coil may be introduced either into the reaction chamber or into the coking chamber or, in part, to each of these zones.

When highly heated products from the secondary charging stock heating coil are supplied 10 to the reaction chamber they are preferably introduced into the upper portion of this zone and are commingled with the heated products supplied thereto from the other heating coil, whereby they furnish additional heat thereto and increase 15 the temperature and rate of cracking in the reaction chamber. In this method of operation, by virtue of the additional heat supplied to the products from the primary charging stock heating coil, the total products, including both 20 their vaporous and liquid components, may be subjected to more severe cracking conditions than those which could safely be employed in a single heating coil and communicating reaction chamber without encountering the excessive formation 25 and deposition of coke in the heating coil. The vaporous components are thereby subjected, in the reaction chamber, to cracking conditions which will affect the production therefrom of a better grade of gasoline and the heavy liquid 30 components of the conversion products may be discharged from the reaction chamber at a sufficiently high temperature to induce their subsequent reduction to coke in the succeeding zone at the reduced pressure employed therein. 35

When highly heated products from the secondary charging stock heating coil are introduced into the coking zone they supply additional heat to the heavy liquid products therein and assist their reduction to substantially dry coke. 40

In the preferred method of operation, a portion of the highly heated products from the secondary charging stock heating coil is introduced, as previously described, into the reaction chamber and another portion of these highly heated 45 products is introduced into the coking zone. The quantity of these highly heated products supplied to the reaction chamber is regulated to affect the optimum degree of cracking in the reaction chamber without the substantial formation 50 and deposition of coke in this zone and the communicating lines, while the quantity supplied to the coking chamber is sufficient to reduce the residual products in this zone to coke of the desired low volatility. 55

Vaporous products are directed from the coking zone to a fractionator wherein their components boiling above the range of the desired gasoline product of the process are condensed as reflux condensate. The vaporous products resulting from such fractionation, preferably comprising gasoline of the desired end boiling point and of good antiknock value, are subjected to condensation and the resulting distillate 10 covered.

The reflux condensate formed by said fractionation is, of course, the result of cracking the two virgin charging stocks and I have found that this reflux condensate contains a substantial amount, at least, of oils which, although of higher boiling characteristics than the secondary charging stock, may be further cracked to better advantage under the relatively severe cracking conditions employed in the secondary charging 15 stock heating coil than under the milder cracking conditions employed for the higher boiling primary virgin charging stock. Therefore, in the present process, such components of the reflux condensate as are suitable for cracking, together with the secondary charging stock, 20 are segregated in the fractionating step from its higher boiling components and supplied for additional cracking to the secondary charging stock heating coil.

I have further found that the relatively high-boiling fractions of the reflux condensate, comprising its components remaining after the separation therefrom of the fractions supplied to the secondary charging stock heating coil, are 25 ordinarily suitable for further cracking under the conditions employed for the primary charging stock, even though they are of higher boiling characteristics or contain a substantial quantity of materials of higher boiling characteristics than the primary charging stock. Such 30 materials are, therefore, in the present process, returned to the primary charging stock heating coil for further cracking.

It will be apparent from the foregoing description of the operation, that it provides a unified 45 process for the selective simultaneous cracking of both light and heavy oils and the reforming of gasoline to produce high yields of gasoline of good antiknock value and minor yields of gas and good quality coke.

I am fully aware that various steps and features of the process such as the reforming of gasoline, the use of a high-pressure reaction chamber and reduced pressure vaporizing chamber 50 connected in series and the production of coke as the residual product of the process are not in themselves new in the art but the improved process of this invention depends upon the cooperative relation of the various steps and features of the process which cooperate in a new and advantageous manner to produce the desired final results.

The accompanying diagrammatic drawing 55 illustrates one specific form of apparatus in which the process of the invention may be conducted.

Referring to the drawing, primary charging stock of the nature previously indicated is supplied through line 1 and valve 2 to pump 3 by means of which it is fed through line 4 and valve 5 to heating coil 6. The oil is heated in this zone to the desired cracking temperature, preferably at a superatmospheric pressure, by means of heat supplied from furnace 7. The heated products are discharged from heating coil 6 through

line 8 and valve 9 preferably into the upper portion of reaction chamber 10.

Chamber 10 is also preferably maintained at a substantial superatmospheric pressure and, although not indicated in the drawing, this zone 5 is preferably insulated to conserve heat. The heated products supplied to chamber 10 pass downwardly through substantially the entire length of this zone and, in the particular case here illustrated, both vaporous and liquid products 10 are withdrawn in commingled state from the lower portion of the reaction chamber and are directed through line 11 and valve 12 into chamber 13.

It is also within the scope of the invention, 15 although not illustrated in the drawing, to separately remove vaporous and liquid conversion products from the lower portion of chamber 10 and to introduce both of these materials into chamber 13 at the same or at separate points 20 in this zone or, when desired, to supply a regulated portion or all of the vaporous products separately withdrawn from chamber 10 directly to fractionator 18 instead of to chamber 13. However, in accordance with the preferred 25 method of operation, the total vaporous and liquid conversion products from chamber 10 are supplied to chamber 13 either as a single stream or as separate streams.

In chamber 13 the heavy residual liquid components 30 separate from the vaporous components of the materials supplied to this zone and are reduced to substantially dry coke, the coking operation being accomplished either with or without the assistance of other highly heated 35 conversion products supplied to this zone, as will be later described, and in either case being assisted by the reduced pressure employed in chamber 13 relative to that utilized in chamber 10.

It is, of course, also within the scope of the 40 invention, when desired, to employ two or more coking chambers, although only one is illustrated in the drawing, and when a plurality of coking chambers is employed they preferably are alternately operated, cleaned and prepared for further 45 operation in order that the coking stage, in common with the rest of the system, may be operated continuously. Coke produced is allowed to accumulate in the coking chamber or chambers in operation and may be removed therefrom in 50 any well known manner, not illustrated, after the coking zone is substantially filled or after its operation has been completed for any other reason.

Chamber 13 is provided with a drain-line 14 55 and valve 15 and this line may also serve, when desired, as a means of introducing steam, water or other suitable cooling material into the chamber, after its operation has been completed and preferably after it has been isolated from the 60 rest of the system, in order to hasten cooling and facilitate removal of the coke therefrom.

Vaporous products are withdrawn from the upper portion of the coking chamber and directed through line 16 and valve 17 into fractionator 65 18, wherein their components boiling above the range of the desired final light distillate product of the process are condensed as reflux condensate.

Fractionated vapors of the desired end-boiling point, consisting preferably of good antiknock 70 gasoline and gaseous products of the process, are directed from the upper portion of the fractionator through line 19 and valve 20 to cooling and condensation in condenser 21. The resulting distillate and uncondensed gases are directed 75

through line 22 and valve 23 to collection and separation in receiver 24. Distillate may be withdrawn from the receiver through line 27 and valve 28 to storage or to any desired further treatment. 5 Unconensed gases may be released from receiver 24 through line 25 and valve 26. When desired, regulated quantities of the distillate collected in receiver 24 may be recirculated by well known means, not illustrated in the drawing, to the 10 upper portion of fractionator 18 to serve as a refluxing and cooling medium in this zone for assisting fractionation of the vapors and to maintain the desired vapor outlet temperature therefrom. 15

15 Simultaneous with the operation above described, secondary charging stock of the character previously mentioned is supplied through line 41 and valve 42 to pump 43 by means of which it is fed through line 44, valve 45 and line 39 20 to heating coil 40.

The oil passing through heating coil 40 is maintained at the desired cracking temperature and preferably at a substantial superatmospheric pressure for a predetermined time, the temperature, pressure and time conditions employed in this zone being regulated to materially improve the antiknock value of the poor quality gasoline or gasoline fractions supplied thereto and to convert the higher boiling oils supplied to this zone 30 into substantial yields of good quality gasoline.

Heated products are discharged from heating coil 40 through line 47 and may be directed, all or in part, into coking chamber 13, entering either the upper portion of this zone through valve 48 35 in line 47 or entering the lower portion of this zone through line 49 and valve 50 or being directed, in part, into both the upper and lower portions of the coking chamber.

All or a regulated portion of the highly heated products from heating coil 40 may, when desired, 40 be directed from line 47 through line 51 and valve 52, preferably into the upper portion of reaction chamber 10 and in the preferred method of operation a regulated portion of the heated products from coil 40 is thus supplied to reaction chamber 10, while the remaining portion is introduced into the coking chamber.

The reflux condensate formed in fractionator 18 is preferably separated, as here illustrated, 50 into selected relatively low-boiling fractions best suited for further cracking in heating coil 40 and the higher boiling fractions which may be cracked to better advantage in heating coil 6.

The high-boiling fractions of the reflux condensate are directed from the lower portion of fractionator 18 through line 29 and valve 30 to pump 31, by means of which they are fed through line 32 and valve 33 into line 4 and thence to heating coil 6.

80 The relatively low-boiling fractions of the reflux condensate, which preferably constitute a major portion of the total reflux formed in the fractionating step, are withdrawn from one or a plurality of suitable intermediate points in the fractionator and directed through line 34 and valve 35 to pump 36 wherefrom they are fed through line 37 and valve 38 into line 39 and thence to heating coil 40, together with the secondary charging stock.

It will be noted, in connection with the drawing and the above description thereof, that the reflux condensate formed in fractionator 18 contains no oil which has not been previously subjected to cracking. Such oils, and particularly 5 those resulting from the cracking of virgin charg-

ing stock, ordinarily require the use of more severe cracking conditions to produce the maximum yields of good quality gasoline than a virgin oil of similar boiling characteristics. The low-boiling fractions of the reflux condensate supplied to heating coil 40 preferably are substantially devoid of materials boiling within the range of the distillate recovered from receiver 24 and are preferably of higher boiling characteristics than the secondary charging stock or 10 contain a substantial quantity of materials boiling above the range of the secondary charging stock. The components of the mixture of previously cracked and virgin oils thus supplied to heating coil 40 are, therefore, suitable for treatment under the same cracking conditions to produce high yields of gasoline of good antiknock value. 15

The high-boiling fractions of the reflux condensate supplied to heating coil 6 preferably are 20 substantially devoid of any components boiling below the range of the primary charging stock supplied to heating coil 6 or within the range of the low-boiling reflux condensate fractions supplied to heating coil 40 and contain any components of the reflux condensate of higher boiling 25 characteristics than the primary charging stock.

It will, of course, be understood that with the fractionating methods and apparatus necessitated by economic considerations there will ordinarily 30 be some overlapping of the various fractions separated in fractionator 18 but preferably, in the present process, the components of the low-boiling fractions of the reflux condensate, which boil within the range of the gasoline product collecting 35 in receiver 24, do not exceed approximately 5 to 6 percent and the components of the high-boiling fractions of the reflux condensate which boil within the range of the lower boiling fractions supplied to heating coil 40 are also kept at a minimum consistent with economic fractionating 40 methods and means.

The preferred operating conditions which may be employed to produce the desired results in an apparatus such as illustrated and above described 45 are approximately as follows: The temperature employed at the outlet from the first mentioned heating coil is preferably of the order of 800 to 950° F. and the pressure employed at this point in the system may range, for example, from 100 to 50 500 pounds, or thereabouts, per sq. in. The temperature employed at the outlet from the second mentioned heating coil may range, for example, from 950 to 1050° F., preferably with a superatmospheric pressure at this point in the system of 55 from 200 to 1000 pounds, or thereabouts, per sq. in. and, as previously mentioned, the temperature and cracking conditions employed in the second mentioned heating coil are more severe than those utilized in the first mentioned heating coil. The 60 pressure employed in the reaction chamber preferably is substantially the same as that employed in the communicating heating coil utilizing the lowest pressure, which is usually the first mentioned heating coil, and the average temperature 65 in the reaction chamber preferably is substantially the same or somewhat higher than that employed at the outlet from the first mentioned heating coil.

The coking chamber is preferably operated at a substantially reduced pressure relative 70 to that employed in the reaction chamber and may range, for example, from 150 pounds, or thereabouts, per sq. in. down to substantially atmospheric pressure. The fractionating, condensing and collecting portions of the system prefer- 75

ably employ superatmospheric pressures substantially the same or somewhat lower than that employed in the coking zone.

As a specific example of the operation of the process of the invention as it may be conducted in an apparatus such as illustrated and above described, the primary charging stock comprises a mid-continent gas oil of about 36° A. P. I. gravity, having an end-boiling point of approximately 720° F. and this material is subjected, together with the components of the reflux condensate boiling above approximately 600° F., to a cracking temperature of approximately 930° F. at a superatmospheric pressure of approximately 400 pounds per sq. in., as measured at the outlet from the heating coil to which these materials are supplied. The secondary charging stock comprises a straight-run gasoline from paraffinic crude and is subjected in a separate heating coil, together with the fractions of the reflux condensate boiling between approximately 400 to 620° F., to an outlet conversion temperature of approximately 1000° F. at a superatmospheric pressure, measured at the outlet from the heating coil, of approximately 650 pounds per sq. in. Approximately 60 percent of the total products from the last mentioned heating coil are supplied to the reaction chamber and the remaining 40 percent, or thereabouts, are introduced into the coking chamber, which latter zone is operated at a superatmospheric pressure of approximately 50 pounds per sq. in. Substantially the same pressure is employed in the fractionating, condensing and collecting portions of the system. This operation will yield, per barrel of total charging stock, approximately 75 percent of 400° F. end-point gasoline having an antiknock value of approximately 70, by the motor method, and approximately 17 pounds of low volatile coke, the remainder being chargeable, principally, to uncondensable gas.

I claim as my invention:

1. A process for the pyrolytic conversion of hydrocarbon oils which comprises heating a virgin charging oil heavier than gasoline to cracking temperature at substantial superatmospheric pressure in a heating coil, introducing the resultant heated products into an enlarged reaction chamber also maintained at substantial superatmospheric pressure, causing both vaporous and liquid components of said heated products to pass through substantially the entire length of said

chamber, withdrawing said products from the chamber and introducing the same into a reduced pressure vaporizing zone wherein vapors are separated from residue, subjecting vaporous products from the vaporizing zone to fractionation, whereby their components boiling above the range of the desired gasoline product of the process are condensed as reflux condensate, subjecting vapors remaining uncondensed by said fractionation to cooling and condensation, recovering as the resulting distillate a good quality gasoline, simultaneously subjecting a secondary virgin charging oil, of lower boiling characteristics than the first mentioned charging oil and containing at least a substantial quantity of components of poor antiknock value boiling within the range of gasoline, to a higher cracking temperature than the first mentioned charging oil and to substantial superatmospheric pressure in a separate heating coil, whereby to materially improve the antiknock value of its gasoline components, commingling highly heated products discharged from said separate heating coil with the heated products from the first mentioned heating coil and causing the commingled materials to pass through substantially the entire length of the reaction chamber, whereby to increase the temperature and rate of cracking of the total products from the first mentioned heating coil in the reaction chamber, supplying to said separate heating coil components of said reflux condensate which are of higher boiling characteristics than said secondary charging oil and are substantially devoid of components boiling within the range of said gasoline product, whereby to subject the same to further cracking with said secondary charging oil.

2. A process such as defined in claim 1 wherein a portion of said reflux condensate is returned to the first mentioned heating coil for further cracking.

3. A process such as defined in claim 1 wherein a regulated portion of said highly heated products discharged from said separate heating coil is introduced into the vaporizing zone.

4. A process such as defined in claim 1 wherein a portion of said reflux condensate is returned to the first mentioned heating coil for further cracking and wherein a regulated portion of said highly heated products discharged from said separate heating coil is introduced into the vaporizing zone.

JACQUE C. MORRELL
